CLAIM

I claim the ornamental design for a caliper crack mark, as shown and described.

DESCRIPTION

FIG. 1 is a top perspective view of a caliper crack mark according to a first embodiment the design;

FIG. 2 is a top plan view thereof;

FIG. 3 is a front elevation view thereof, the left, right and rear elevation views being identical;

FIG. 4 is a cross-section view thereof taken along the line 4-4 of FIG. 3;

FIG. 5 is a bottom perspective view thereof;

FIG. 6 is a bottom plan view thereof;

FIG. 7 is a top perspective view of a caliper crack mark according to a second embodiment of the design;

FIG. 8 is a top plan view thereof;

FIG. 9 is a front elevation view thereof, the left, right and rear elevation views being identical;

FIG. 10 is a cross-section view thereof taken along the line 10-10 of FIG. 9;

FIG. 11 is a bottom perspective view thereof;

FIG. 12 is a bottom plan view thereof;

FIG. 13 is a top perspective view of a caliper crack mark according to a third embodiment of the design;

FIG. 14 is a top plan view thereof;

FIG. 15 is a front elevation view thereof, the left, right and rear elevation views being identical;

FIG. 16 is a cross-section view thereof taken along the line 16-16 of FIG. 15;

FIG. 17 is a bottom perspective view thereof; and,

FIG. 18 is a bottom plan view thereof.

The stippled shading in the Figures shows surface contouring and does not represent surface ornamentation.
